Attorney

UNITED STATES PATENT OFFICE.

GEORGE W. LARD, OF ARBUCKLE, OKLAHOMA.

SAFETY-VALVE FOR CANS.

1,280,250.

Specification of Letters Patent.

Patented Oct. 1, 1918.

Application filed March 21, 1917. Serial No. 156,425.

To all whom it may concern:

Be it known that I, GEORGE W. LARD, a citizen of the United States, residing at Ar-
buckle, in the county of Murray and State
5 of Oklahoma, have invented certain new and
useful Improvements in Safety-Valves for
Cans, of which the following is a specifica-
tion, reference being had to the accompan-
ying drawings.

10 This invention relates to safety closures
for oil cans, gasoline cans, and other con-
tainers of like character designed to contain
explosive fluids.

The general object of the invention is to
15 provide means for normally closing the
spout of an oil can and the air inlet opening
of an oil can, so as to prevent spilling of the
contents of the can or container, or igni-
tion of the contents.

20 A further object of the invention is to
provide means whereby the valve closing
the spout of the oil can may be readily
opened and held open by a pressure of the
operator's thumb, while the oil is being
25 poured therefrom and will close as soon as
the pressure is released.

A further object is to provide an im-
proved means for admitting air to the in-
terior of the container, which includes a clo-
30 sure normally held to its seat to prevent the
admission of air, but which may be forced
open by the operator and if desired may be
manipulated so as to hold the closure open
while the oil is being poured.

35 Other objects of my invention relate to
the details of construction and improve-
ments in the arrangement of the parts, as
will hereafter appear.

The invention is illustrated in the accom-
40 panying drawings, wherein:—

Figure 1 is a fragmentary vertical sec-
tional view of a can provided with my im-
proved valves;

Fig. 2 is a like view to Fig. 1 but showing
45 the valves open;

Fig. 3 is a sectional view on the line 3—3
of Fig. 2 looking upward;

Fig. 4 is a top plan view of a portion of
the top of the can showing the housing 22;

50 Fig. 5 is a perspective view of the tubular
member 29;

Fig. 6 is a perspective view of the valve
34 detached.

Referring to the drawings, it will be seen
55 that I have illustrated an oil can or container
10, such as used for containing gasoline,

kerosene, and other highly explosive fluids,
this can being provided with a spout 11.
The spout may be of any suitable form or
dimensions, but preferably is tapered to-
ward its pouring extremity and extends into
the top of the can, or the wall of the can, a
distance of about $\frac{1}{2}$ of an inch. Coacting
with this spout and normally closing pas-
sage therethrough is a valve comprising a 65
disk 12 of cork, rubber or other suitable ma-
terial, but preferably cork, which is dis-
posed within a circular holder 13 forming
part of an arm 14, which extends away from
the end of the spout 11 and is pivoted be-
tween ears 15 attached to or formed as part
of the can wall. The cork 12 is highly com-
pressed before it is inserted in the ring 13
and is preferably deeper than this ring 13,
so that the portion of the cork which pro-
jects above the ring is not as tightly com-
pressed and is compressible by contact with
the butt end of the spout 11. 70

For the purpose of normally holding the
valve closed, I provide a stem 16, which ex-
tends through the top of the oil can and is
slotted for the passage of the arm 14. Sur-
rounding the opening through which this
stem passes, and disposed upon the exterior
face of the can, is a tubular member 17, and 80
disposed around the opening through which
the stem 16 passes, and within this tubular
member, is a packing 18 of cork, or other
suitable material, which will prevent the
escape of liquid or vapor through the open-
ing. Surrounding the stem 16 and disposed
90 within the tubular member 17 is a spring 19
and carried by the upper end of the stem
16 is a push button or cap 20, which is
firmly attached to the stem and which is
countersunk, as at 21, to receive the upper
end of the spring 19, so as to permit as long
a spring as possible to be used. The body of
the push button extends down into the tubu-
lar member 17, the head of the push button 100
being larger than the tubular member.

For the purpose of housing the parts and
protecting them from damage, I preferably
provide the housing 22, which has a top wall
and side walls. The top wall at one end is 105
cut away as at 23 to extend around the spout
11 and the side walls engage with the spout.
This housing may be made of one piece of
sheet metal stamped out in proper form and
brazed, soldered, or otherwise attached to 110
the top of the can and to the spout 11. This
housing is formed with an opening 24 and

the margin of this opening 24 is depressed as at 25 so that the edge of the opening is level with the top of the tube 17. The push button has its head 20 disposed above the top 5 of the housing, but the depression 25 is of sufficient depth so that the push button is at all times disposed below the plane of the top plate of the housing and thus is at all times protected.

10 It will be obvious that by depressing the push button 24, the valve will be shifted away from the end of the spout 11 against the force of the spring 19 and that as soon as the pressure is released upon the push 15 button, the spring 19 will return the parts to their original position.

For the purpose of admitting air to the can, while the contents are being poured out, I provide a cap 26 which is made of sheet 20 metal, and which has a screw-threaded annular flange 27 adapted to engage the screw-threaded flange 28 surrounding the inlet opening of the can. This cap is depressed at its center and has a central opening in 25 which is disposed a vertically extending tube 29, the upper end of which is outwardly flared as at 30. Across the lower end of this tube extends a plate 31, having a central perforation and a plurality of air holes 32 disposed around the central perforation. 30 Extending through the central perforation is a stem 33 of a valve 34. This stem extends upward through the tubular member 29 and at its upper end is attached to a cap 35 con- 35 stituting a push button, the cap having a marginal flange 36 which is adapted to extend down and around the tube 29, the flared ends of the tube engaging with the side walls of the cap. The inner face of the cap is pro- 40 vided with the inwardly projecting lug 37. The tubular member 29 is formed at its upper end with a bayonet slot 38, with which the lug 37 is adapted to coact and adjacent its upper end the tube 29 is also formed with 45 a plurality of perforations 39. Preferably the valve 34 is formed with an outer cup-shaped metallic member attached to the stem 33 and a cork filling 40, the valve 34 being of sufficient diameter so that the cork 40 will 50 bear against the lower face of the plate 31 when the valve is raised.

It will be seen that ordinarily the valve 34 will be held against the plate 31 by means of a spring 41, which surrounds the stem 33 55 and bears at its lower end against the plate 31 and urges the valve upward. Under these circumstances, air cannot pass into the body of the can, but if the valve be pushed down air can pass through the perforations 60 39 and 32 into the can, the flared upper end of the tube 29 preventing the lateral flange 36 of the cap 35 from obstructing these perforations 39. If it be desired to hold the valve open, without the necessity of exerting 65 manual pressure on the valve, then the cap

35 is turned, after being forced down, until the engagement of the lug 37 with the bayonet slot 38 holds the valve open.

The operation of the invention will be obvious from what has gone before and the 70 advantages of the device are plain. It will be seen that these valves 12 and 34 will prevent any leakage from the can in case the can is tipped over and will also prevent the 75 evaporation of the oil. This is particularly of value where very volatile oil, such as gasoline or naphtha, are contained within the can. When it is desired to use the can, both 80 valves are opened in the manner heretofore described and the contents poured out in the 85 usual manner. When the valves are closed, they will prevent any explosive vapor from passing out of the can and hence the danger of igniting the gaseous contents of the can, and thereby causing explosion, will be mini- 90 mized. It will further be observed that both valves are held to their seats positively by springs and that the cork filling or packing of each valve will make it certain that the valves seat properly so as not to permit the 95 leakage of explosive gases. The cap 26 is depressed at its center so that the push button does not project above the top of the cap and thus there will be no danger of the button being accidentally depressed while 95 the can is being transported. The same is true in regard to the push button 20, which is disposed sufficiently below the upper face of the housing 22 as to be held from accidental movement.

100 It will be seen, of course, that the housing 22 protects the valve structure from damage, due to rough handling of the can, or any depression of the top and that the valve 40 is also fully protected by the housing 29 and 105 by the recessed or depressed portion of the cap 26.

While I have illustrated a flat top can, it is to be understood that this is purely illustrative and that my construction may be 110 applied to a round top can, just as well as to a flat top can.

It will be seen that my device is very simple, can be readily applied to all forms of cans or containers and that it has many advantages over the ordinary spouts and air inlets for cans of this character. While I have illustrated a particular form of my invention, it will be understood that many changes might be made, without departing 120 from the spirit thereof.

Having described my invention, what I claim is:

1. An oil can having an opening defined by upwardly extending walls, a cap having 125 screw-threaded engagement with said walls and having a depressed central portion, a tubular member extending through the depressed portion of the cap, a valve normally closing the opening through the cap, and a 130

button disposed over the end of the tubular member and operatively connected to the valve and normally disposed below the level of the uppermost portion of the cap.

- 5 2. An oil can having a top, a cup-shaped member extending through the top and outwardly flared at its upper end and formed with air inlet perforations in its side wall and perforations in its bottom, a valve normally closing said last named perforations, a spring disposed within the cup-shaped member and urging the valve to its closed position, and a button operatively connected to the valve and extending over the top of the cup-shaped member and having downwardly extending flanges spaced from the body of the cup-shaped member by said flared upper portion thereof.
3. An oil can having a top, a cup-shaped member extending through the top and outwardly flared at its upper end and formed with air inlet perforations in its side wall and perforations in its bottom, a valve normally closing said last named perforations, a spring disposed within the cup-shaped member and urging the valve to its closed position, a button operatively connected to the valve and extending over the top of the cup-shaped member and having downwardly extending flanges spaced from the body of the cup-shaped member by said flared upper portion thereof, and means for locking the button in a depressed position with the valve open.
- 20 4. An oil can having a top, a cup-shaped member extending through the top, a valve controlling passage through said cup-shaped member and having a stem extending upward therethrough, a button mounted on the stem and having a downwardly extending side wall embracing the cup-shaped member, a spring urging the button upward and the valve to a closed position, and a pin extend-

ing inward from the side wall of the button, the cup-shaped member having a bayonet slot with which the pin engages.

5. An oil can having an inlet opening, a cap for closing said opening and having a depressed central portion, a cup-shaped member extending through the depressed portion and having its upper end flared and perforated, the bottom of the cup-shaped member being provided with perforations, a valve having a stem extending upward through the lower end of the cup-shaped member and having a push button at its upper end and having a flange extending down over the flared portion of the cup-shaped member, and a spring disposed within the member and normally holding the valve closed.

6. An oil can having an inlet opening, a cap for closing said opening and having a depressed central portion, a cup-shaped member extending through the depressed portion and having its upper end flared and perforated, the bottom of the cup-shaped member being provided with perforations, a valve having a stem extending upward through the lower end of the cup-shaped member and having a push button at its upper end and having a flange extending down over the flared portion of the cup-shaped member, and a spring disposed within the cup-shaped member and normally holding the valve closed, said valve comprising a metallic shield and a compressive packing disposed within the shield and adapted to be forced against the lower end of the cup-shaped member.

In testimony whereof I hereunto affix my signature in the presence of two witnesses.

GEORGE W. LARD.
